DESIGN FOR A CHAIR OR SIMILAR ARTICLE

Jackson D. Rogers, Bay Village, Ohio

Application January 17, 1938, Serial No. 74,345

Term of patent 7 years

To all whom it may concern:

Be it known that I, Jackson D. Rogers, a citizen of the United States and a resident of Bay Village, in the county of Cuyahoga and State of Ohio, have invented a new, original, and ornamental Design for a Chair or Similar Article, of which the following is a specification, reference being had to the accompanying drawing, forming a part thereof.

In said drawing, Fig. 1 is a perspective view of a chair, showing my new design; Fig. 2 is an enlarged elevational view of a portion of the back member of such chair; Fig. 3 is a cross-sectional view of the portion shown in Fig. 2, on the line 3—3, Fig. 2; and Fig. 4 is a detail longitudinal sectional view of a portion of the leg supporting member of such chair, on the line 4—4, Fig. 1.

I claim:

The ornamental design for a chair or similar article, as shown.

JACKSON D. ROGERS.
